INTERNAL COMBUSTION ENGINE

Joseph S. Coates, Goshen, N. Y.

Application April 25, 1938, Serial No. 204,241

2 Claims. (Cl. 123—71)

This invention relates particularly to internal combustion engines in which ignition of the fuel occurs every time the piston approximately reaches the end of the outward or upward stroke, erroneously called two cycle engines, but the improvements also are applicable to two stroke Diesel engines using the injection method of fuel and some of the improvements may be applied to other internal combustion engines.

10 Among numerous objects, one of great importance is to produce a pure fuel, stored under pressure and held in storage while combustion pressure has driven the piston almost the entire length of its stroke and the spent gases have 15 started on their way out of one end of the cylinder before fresh fuel is admitted at the opposite end, thereby avoiding the common and usual mixing of spent gases with pure fuel.

Another object is to provide and use that particular proportion of air and vaporized fuel which yields the greatest power when ignited, but which is impossible in present day engines due to the existence of flame in the cylinder when 20 fresh fuel is admitted, thereby requiring a richer mixture which is slower to ignite, a fact which is made evident by the back-fire to the carburetor, common to the starting of a cold engine, but which is instantly checked by pulling the choke 25 throttle and enriching the mixture.

Another object is to provide for each power cylinder of an engine, a storage reservoir for fuel under pressure and in sufficient volume to insure filling of the cylinder at a pressure higher than atmosphere.

30 Another object is to utilize in the most efficient manner, the evaporation of the fuel as a means to cool the piston and simultaneously to utilize the heat of the piston to complete the vaporization of the fuel which no carburetor can complete.

Another object is to provide in advance of its use, a volume of fuel, under pressure stored in a reservoir attached to the cylinder which pressure automatically increases with the increase 40 in engine speed, thereby largely through the increased pressure compensate for the shortened period of time, at high speeds, during which time fuel can pass into the cylinder from the reservoir through the valve for that purpose, likewise the 45 pressure in the reservoir decreases with decreased engine speed.

Another object is to provide a greater area for the exhausting of the spent gases by utilizing more of the circumference of the cylinder wall than has heretofore been feasible.

Another object is to eliminate parts and simplify the engine and to reduce the weight and the cost per horsepower.

Additional objects, advantages and features of invention will be apparent from the following 5 description considered in conjunction with the accompanying drawings, wherein

Figure 1 is a vertical section through the engine.

Figure 2 is a cross section on the line 2—2 of 10 Figure 1.

Figure 3 is a plan view of a packing ring employed in the engine.

Figure 4 is a fragmentary cross section thereof.

In carrying out the invention, I provide a 15 crank case 10 of any approved construction upon which there is mounted tandem cylinders 11 and 12, each of which is cored as at 13', to provide passage of a cooling liquid, as is customary.

The cylinder 11 is of greater diameter than 20 the cylinder 12, and the piston 13 therefore, has an enlarged base 14, complementary to the cylinder 11 and a reduced portion 15 is slidably engaged in the cylinder 12. Thus, a chamber 16 is provided in the cylinder 11 and into the upper 25 end thereof a port 17 is formed. Diametrically opposite, a port 18 is provided, establishing connection with a carburetor (not shown) by way of a rotary valve 19 and pipe 20, which will be described hereinafter in detail.

At the upper end of the cylinder 12 an opening 30 is formed in which a valve cage 21 is secured, as by a clamp collar 22, the cage having a poppet valve 23 mounted therein, adapted to open upon the cylinder 12 when actuated by the cam 24 35 driven at engine speed through suitable means associated with the crank shaft. The valve 23 includes a spring 25 for normally holding the valve closed.

The cylinder 12 has a laterally extended port 40 26 in registry with a port 27 formed in the valve cage 21, and with the former port there is secured a pressure fuel reservoir 28, the latter extending downwardly parallel to the cylinders 11 and 12 and has an opening 29 for registry 45 with the port 17 of the cylinder 11.

At the side opposite the port 17, the reservoir 46 has a threaded opening to receive a valve guide 30. The guide comprises a sleeve 31 receiving the stem 32 of a poppet valve 33, adapted to seat 50 upon and control passage of fuel through the port 17, the valve being held closed by a spring 34.

In the bottom of the reservoir 28 there is secured a ball valve 35, which in the present instance is shown as mounted in a cage 36, the 55

- lower end of which is interiorly threaded to receive a screw plug 37. A helical spring 38 is interposed between the upper end of the plug and the ball 35 to hold the ball against its seat.
- 5 A cup 39 is threadedly engaged upon the lower end of the cage 36, and has a removable plug 40 in the base thereof aligned with the plug 37 in order that the plug 37 may be adjusted to vary the tension of the spring 38, upon removal of
- 10 the plug 40. A pipe 41 opens upon the cup 39 and leads to the main fuel tank 39' and by reason of this connection condensed vapor which may occur is conducted back to its original source.

The cylinders 11 and 12 are formed as separate members suitably bolted together in end to end relation, and in the base of the cylinder 12 an annular recess 42 is formed, seating a constrictive ring 43, which will now be described, reference being had to Figures 3 and 4. The ring 43 is of a diameter slidably receiving the piston 15 therethrough and comprises a pair of superposed ring members 44, the abutting face edges being grooved peripherally as at 45 to receive and seat a garter spring 46. The ring members 44 have 25 their split portions 47 positioned diametrically opposite each other, and the contacting faces of the rings are provided with a plurality of radially spaced grooves 48, extending from the inner to the outer peripheries of the members, these 30 grooves serving as oil passages feeding oil to the rings and piston by way of the oil duct 49.

The ring 43 is preferably held in place by means of a plate 50 secured between the abutting upper and lower ends of the cylinders 12 and 11, and one or both of the cylinders may be recessed to accommodate the plate.

The cylinder 12 adjacent its base is provided with a plurality of exhaust ports 51 extending half way or more around the cylinder circumferentially, the ports being in communication with a semi-annular passage 52, for discharge into an exhaust pipe 53. Obviously, for an engine automatically exhausting spent gases at the bottom of the cylinder, it is absolutely essential to provide a large exhaust area to obtain complete scavenging of gases, and the construction described greatly increases the exhaust area, as compared with the usual plan of utilizing only part of a side of a cylinder.

The construction and operation of the valve 19 will now be dealt with, reference being made to Figures 1 and 2. As may be seen the valve is of the rotary plug type, having a transverse port 54, the valve being suitably housed in a cage 55, the latter being bolted to the side of the cylinder 11 so that the port 54 will register with the port 18, at times. The valve 19 includes a shaft 56 upon which there is keyed a sprocket wheel 57 adapted to be driven by a suitable chain. The shaft will be of a length to extend to all cylinders which the engine may comprise and preferably between each two cylinders there is provided a universal joint 58, diagrammatically shown.

The operation

The operation of the engine with carburetor throttle wide open is best described by assuming the combustion space in the top of the power cylinder filled with compressed fuel, the piston being very nearly at top center and fuel storage reservoir 28 filled at maximum pressure. Ignition takes place by spark plug 59 and the piston descends on its power stroke during which movement the enlarged base 14 of the piston in the lower and larger cylinder is drawing fuel, by

suction, from the carburetor through the rotary valve 19, which opened when the piston started to descend. When the top of the piston has descended to a position about three-eighths of an inch or more below the top of the exhaust ports 51, the overhead valve 23 opens to admit fuel from the fuel reservoir into the power cylinder, thus the exhaust gases start going out before the fresh fuel starts coming in. During the further travel of the piston to bottom center and its upward movement so that the exhaust ports are closed the spent gases have entirely passed out of the exhaust ports and during the time that the piston was moving as just described the valve 23 was open and is about to close. Simultaneously, 15 the step of the piston in the lower cylinder having reached bottom center and risen slightly the valve 19 from the carburetor has closed and both cylinders are filled with fuel. The further rise of the piston to top center results in highly compressing the fuel in the upper cylinder 12, simultaneously forcing the fuel in the lower cylinder 11, through the valve 32 into the storage reservoir 28, thereby restoring the pressure therein, which had been depleted when the overhead 20 valve 23 was previously opened. That completes the operation of the two strokes of the piston, one stroke in every two being a power stroke. The overhead valve 23 is not opened until the piston has practically reached bottom 25 center, hence the fuel is held in storage during the period of time required for the piston 15 to move practically one stroke, or at least 85% thereof.

I assert that my objects as heretofore set forth have been attained, which an analysis of the exhaust gases of this engine taken by a responsible laboratory clearly shows. This engine exists and is in operation. The analysis of the exhaust shows 98.5% of the fuel burned, .003% of carbon monoxide, compared to a test taken the same day of a standard make of a four cycle engine, which showed 78% of the fuel burned, 4.5% of carbon monoxide.

I claim:

1. In an internal combustion engine of the two-stroke type, a pair of tandem cylinders, one of the cylinders having a diameter greater than the other, a piston, said piston having portions complementary to respective cylinders, a fuel intake port opening upon the larger cylinder, valve means for controlling passage of fuel to the cylinder, a fuel reservoir, the larger cylinder having a port opening upon the reservoir, a valve constructed for admitting fuel under pressure from the cylinder to the reservoir, the reservoir having communication with an upper portion of the smaller cylinder, a valved by-pass associated with the reservoir for return of condensed vapors to its original source, a valve cage in the smaller cylinder, said cage having a port in communication with the reservoir and further having a valve seat opening upon the cylinders, a poppet valve reciprocably mounted in the cage, a cam operable at engine speed for reciprocating the valve, said smaller cylinder having a plurality of exhaust ports adjacent the base of the cylinder, said ports being spaced circumferentially for half way or more of the cylinder, and an exhaust chamber complementary to the exhaust ports.

2. In an internal combustion engine of the two-stroke type, a pair of tandem cylinders, one of the cylinders having a diameter greater than the other, a piston, said piston having portions complementary to respective cylinders, a fuel in-

take port opening upon the larger cylinder, valve means for controlling passage of fuel to the cylinder, a fuel reservoir, the larger cylinder having a port opening upon the reservoir, a valve constructed for admitting fuel under pressure from the cylinder to the reservoir, the reservoir having communication with an upper portion of the smaller cylinder, a valved by-pass associated with the reservoir for return of con-

densed vapors to its original source, a valve cage in the smaller cylinder, said cage having a port in communication with the reservoir and further having a valve seat opening upon the cylinders, a valve reciprocably mounted in the cage, means operable at engine speeds for reciprocating the valve, and exhaust ports at the base of the smaller cylinder. 5

JOSEPH S. COATES.
